(57) CLAIM

The ornamental design for a golf purse, as shown and described.

DESCRIPTION

FIG. 1 is a left-side, top and front exterior perspective view of one embodiment of golf purse in accordance with one aspect of my new design;

FIG. 2 is an exterior front view thereof;

FIG. 3 is a left side view thereof;

FIG. 4 is a right side view thereof;

FIG. 5 is an exterior rear view thereof;

FIG. 6 is a top plan view thereof, with the strap removed;

FIG. 7 is a left-side interior and exterior top and front perspective view thereof;

FIG. 8 is a right-side interior and exterior top and front perspective view thereof;

FIG. 9 is a left-side top and front exterior perspective view of an alternative embodiment of a golf purse shown in FIGS. 1-8, with portions having different colored surfaces in accordance with the new design;

FIG. 10 is an exterior front view thereof.

FIG. 11 is a left side view thereof, a right side view being a mirror image thereof;

FIG. 12 is an exterior rear view thereof.

FIG. 13 is a left-side top and front exterior perspective view of another alternative embodiment of a golf purse shown in FIGS. 1-8 with portions having different colored surfaces in accordance with the new design;

FIG. 14 is an exterior front view thereof; and,

FIG. 15 is an exterior rear view thereof.

The broken lines showing a strap, buckles, round decoration and the purse interior are for the purposes of illustrating environment and form no part of the claimed design. The broken lines showing stitching are part of the claimed design.
